(57) **CLAIM**

The ornamental design for a solar charging stand, as shown and described.

DESCRIPTION

FIG. 1 is a front elevational view of a solar charging stand according to our new design;

FIG. 2 is a rear elevational view of the solar charging stand;

FIG. 3 is a left side elevational view of the solar charging stand;

FIG. 4 is a right side elevational view of the solar charging stand;

FIG. 5 is a top plan view of the solar charging stand in the retracted position;

FIG. 6 is a bottom plan view of the solar charging stand in the retracted position; and,

FIG. 7 is an upper right perspective view of the solar charging stand.
